HAIR CURLER

William Huppert, New York, N. Y., assignor to
Delamere Company, Inc., a corporation of
Delaware

Application March 26, 1936, Serial No. 70,921

6 Claims. (Cl. 132—41)

This invention relates to improvements in a hair curler, and more particularly to a hair curler or waver of the type comprising two pivotally connected cooperating members around which the hair is wound, and a swingable loop element adapted to embrace the wound hair to prevent it from unwinding.

Among the objects of the present invention are to provide a hair curler in which the two cooperating members are pivoted together independently of the loop element, in which the loop element is secured against accidental disconnection or undesirable side-play, and which has means for centering and locking the loop element in its closed position.

Other objects and advantages of the invention will appear from the following description, reference being had to the accompanying drawing, in which:

20 Figure 1 is a side view of the curler showing the two cooperating members and the loop element in closed positions;

Fig. 2 is a bottom plan view of the same;

Fig. 3 is a bottom plan view on an enlarged scale of a portion of one of the cooperating members;

Fig. 4 is a longitudinal sectional view of a portion of the other of said cooperating members;

Fig. 5 is a cross-sectional view showing said members in one stage of assembly; and

Fig. 6 is a sectional view, taken on the line 6—6 of Fig. 1, showing said parts fully assembled.

The device generally described comprises a tubular cylindrical curling member 10, a semi-cylindrical clamping member 11, which parts are pivotally connected at 12, and a swingable wire loop element 13. A spring 14, indicated by the dotted lines in Figure 1, may be provided to urge the members 10 and 11 closed. Each member 10 and 11 may be formed with a finger grip portion 15 at one end, and each has a pair of parallel lugs or ears 16 and 17, respectively. The ears 16 of the semi-cylindrical member 11 overlap the ears 17 of the cylindrical member 10.

45 The lugs 16 of the member 11 are provided with inwardly extending annular bearings 18 as shown in Figs. 3, 5 and 6. These bearings may be conveniently formed by extruding, drawing, or punching, and they have central apertures through which the inturned ends 19 of the loop element 13 are inserted. A split sleeve or cylindrical clamp 20 embraces the two inturned loop-ends 19 and secures them together, the sleeve or clamp 50 being squeezed tightly about said ends. The sleeve

20 is narrower than the width of the space between the opposed bearings 18. The loop element 13 is preferably secured to the member 10, and the inturned ends of the loop are fastened together, before the member 10 is secured to the member 11.

The lugs 17 of the member 10 have apertures 21 which fit on the bearings 18 of the companion member to pivotally connect the two members together. Slots 22 lead downwardly into the apertures 21, the slots being slightly wider than the diameter of the wire of the loop ends 19.

In assembling the device, the lugs 17 are bent slightly toward each other, as shown in Fig. 5, and the loop ends 19 are passed downwardly through the slots 22 into the apertures 21, after which the lugs are spread apart, as shown in Fig. 6, so that the apertures 21 of the lugs 17 engage on the bearings 18 of the lugs 16. Bending of the lugs is unnecessary when they are made of spring metal.

The member 10 may be provided with a circumferentially extending rib 23 adjacent the point of pivotal connection, and the member 11 may be formed with a similar rib 24. The ribs may be pressed or stamped in the metal of the parts and they serve to strengthen the parts.

The free end or bight 25 of the loop element 13 carries a cylindrical roller 26, which roller, in closed position of the loop, engages in the open tubular end of the member 10. The roller 26 is preferably made of a solid material, such as the material commonly known as acetate. The sides 27 of the free end of the loop lie parallel to each other and are separated a distance slightly greater than the diameter of the outer end of the member 10. This provides a construction whereby the loop is locked and centered in closed position.

I am aware that prior to my invention hair curlers have been made with two cooperating members pivotally connected by means of the inturned ends of a wire loop element, such as shown for example in Letters Patent No. 1,739,301 to Abraham Goodman and Jacob Goodman. I believe however that I am the first to construct hair curlers of such character that the cooperating members are pivotally connected together independently of the wire loop element and in which the inturned ends of the wire loop element are clamped together prior to securing one of the cooperating members to the other.

struction herein described may be made within the scope of the invention.

What I claim is:—

1. In a hair curler, a tubular member having 5 lugs at opposite sides adjacent one end, a semi-tubular member having lugs at opposite sides adjacent one end, the lugs of the semi-tubular member overlapping the lugs of the tubular member, inwardly extending annular bearings on the 10 lugs of the semi-tubular member, apertures in the lugs of the tubular member which fit on said bearings to pivotally connect the two members together, a wire loop element having inturned ends that pass inwardly through said bearings, 15 and a clamp tightly embracing said inturned ends intermediate the bearings.

2. In a hair curler, a tubular member having lugs at opposite sides adjacent one end, a semi-tubular member having lugs at opposite sides 20 adjacent one end, the lugs of the semi-tubular member overlapping the lugs of the tubular member, inwardly extending annular bearings on the lugs of the semi-tubular member, apertures in the lugs of the tubular member which fit on 25 said bearings to pivotally connect the two members together, slots in said lugs leading to said apertures, a wire loop element having inturned ends that pass inwardly through said bearings, and a clamp tightly embracing said inturned ends 30 intermediate the bearings.

3. In a hair curler, a tubular member having lugs at opposite sides adjacent one end, a semi-tubular member having lugs at opposite sides adjacent one end, the lugs of the semi-tubular 35 member overlapping the lugs of the tubular member, inwardly extending annular bearings on the lugs of the semi-tubular member, apertures in the lugs of the tubular member which fit on said bearings to pivotally connect the two members 40 together, a wire loop element having inturned

ends that pass inwardly through said bearings, a clamp tightly embracing said inturned ends intermediate the bearings, and a cylindrical roller on the bight of the loop for engagement in the open end of the tubular member.

4. In a hair curler, a pair of cooperating hair rolling members, a wire loop member embracing the hair wound on said members, said loop member having inturned ends on which the loop is pivoted, and a sleeve tightly engaging said inturned ends to secure them together within the curler.

5. In a hair curler, a tubular member and a semi-tubular member, said semi-tubular member having lugs at opposite sides adjacent one end, inwardly extending annular bearings on said lugs, a wire loop element having inturned ends passing inwardly through openings in said bearings, a clamp binding said ends together intermediate said bearings, said clamp being shorter than the space between the bearings, lugs at opposite sides of the tubular member adjacent one end thereof, apertures in said lugs which fit on said bearings to pivotally connect the tubular and the semi-tubular members, slots in said lugs 25 leading to said apertures, said slots being wider than the diameter of the wire of the loop element, said loop element being attached to the semi-tubular member and having its inturned ends fastened together before said semi-tubular member is pivotally secured to the tubular member.

6. In a hair curler, a tubular form around which the hair is wound, a wire loop member adapted to embrace the hair wound on said form, said wire loop having inturned ends which extend inwardly into the bore of the tubular form, and a coupling element connecting said inturned ends within the bore of the form.

WILLIAM HUPPERT. 40
